UNITED STATES PATENT OFFICE.

CHARLES L. POND, OF BUFFALO, NEW YORK.

METALLIC SEAL.

SPECIFICATION forming part of Letters Patent No. 331,439, dated December 1, 1885.

Application filed August 18, 1885. Serial No. 174,734. (No model.)

To all whom it may concern:

Be it known that I, CHARLES L. POND, of the city of Buffalo, in the county of Erie and State of New York, have invented new and 5 useful Improvements in Metallic Seals, of which the following is a specification.

This invention relates to an improvement in that class of metallic seals which are composed of a disk of soft metal and a shackle-wire which passes through openings in the seal-disk.

The object of this invention is to render the seal more secure and convenient in use; and the invention consists of the improvements 15 which will be hereinafter fully set forth, and pointed out in the claims.

In the accompanying drawings, Figure 1 is a face elevation of my improved seal. Fig. 2 is a vertical section of the same before it is 20 pressed. Fig. 3 is a similar view after it is pressed. Fig. 4 is a sectional view parallel with the face of the seal-disk. Fig. 5 is a perspective view showing a slightly modified construction of the seal-disk. Fig. 6 is a vertical section of the same seal before it is pressed. Fig. 7 is a similar view showing the seal after 25 it is pressed. Fig. 8 is a perspective view showing the wire-orifice of the seal-disk reinforced.

30 Like letters of reference refer to like parts in the several figures.

A represents the seal-disk, constructed of soft metal, and b represents the shackle-wire, which may be attached to the seal-disk by casting 35 the latter on one end of the wire, or which may be detached from the seal-disk and be inserted with both ends in orifices formed in the same.

c is a recess or depression formed in one side 40 of the seal-disk, and d is a raised portion or enlargement formed on the opposite side of the seal-disk in line with the depression c. The threading orifice or orifices e pass through that portion of the seal-disk which lies between the depression c and enlargement d, as clearly 45 represented in Figs. 2 and 6. The depression c and enlargement d may extend across the seal-disk at right angles to the threading-hole, as represented in Figs. 1 and 8, or they may

be arranged centrally on the seal-disk, as represented in Figs. 5 and 6.

Upon inserting the end of the shackle-wire b into the threading orifice e, and pressing the seal in the press, the dies of the press exert their pressure first upon the enlargement d 55 and the flat portions on both sides of the recess c, whereby the metal of the disk which lies between the bottom of the recess c and the surface of the enlargement d is displaced with reference to the other portions of the disk, carrying the embedded portions of the wire with it until the disk is flattened out, as represented in Figs. 3 and 7. By this displacement of a portion of the seal-disk the portions of the wire embedded in the same are bent, corrugated, or crimped, whereby the wire is firmly 60 secured in the disk and prevented from being withdrawn therefrom without defacing the impression or otherwise showing that the seal has been tampered with. It is obvious that a 65 number of such depressions and enlargements may be arranged along the threading orifice or orifices, if desired. When the seal is very thin, the wire-orifices are preferably reinforced within the recess by semi-tubular enlargements f, as represented in Fig. 8.

I claim as my invention—

1. A soft-metal seal-disk provided on opposite sides with a depression and an enlargement, and having a wire-orifice formed in the 80 seal-disk between said depression and enlargement, whereby the wire inserted in said orifice is bent or corrugated upon pressing the seal-disk, substantially as set forth.

2. A soft-metal seal-disk provided on opposite sides with a depression and enlargement extending across the seal-disk, and orifices for the shackle-wire formed through the seal-disk between said depression and enlargement and about at right angles to the same, substantially as set forth.

Witness my hand this 15th day of August, 1885.

CHARLES L. POND.
